SPACING STIRRUP FOR HOLDING AND SPACING TUBULAR MOLDING FORMS

Emmett V. Poston, Springfield, Ill., assignor to Poston Springfield Brick Company, Springfield, Ill., a corporation of Illinois

Application March 6, 1940, Serial No. 322,587

5 Claims. (Cl. 72—122)

My invention relates to devices used in connection with pouring and setting cementitious forms; an object being in my device to provide a support and spacer for reinforcements and coring forms in conjunction with the making of structural forms.

A further object of my invention is to provide in an integral stirrup construction, a convenient, economical and simple device not only adapted to support reinforcing rods and coring tubes in "forms" when pouring cementitious materials for producing structural members, but also, to provide in such stirrups a substantial and practical means of spacing these reinforcing rods and coring tubes in a predetermined interspace relationship in the cementitious mass of the structural member.

A particular purpose of my device is to provide an integral stirrup which will be economical to make, simple to handle and very effective as a support and spacer for reinforcing rods and coring tubes for cementitious structural members, and in such a stirrup a construction permitting such rods to be conveniently laid in place and permitting coring tubes to be set in place and held in their desired spaced position while the cementitious material is being poured in place about the stirrups, rods, and coring forms before the material sets and hardens.

I achieve the purposes of my invention by the device described in this specification, recited in the claims and illustrated in the drawing:

In the drawing it will be noted that:

Figure 1 is a perspective of one form of my stirrup.

Figure 2 is a perspective of another and coiled form of my stirrup.

Figure 3 is a cross-section of a cementitious structural member with my stirrup set in position to space and support the reinforcing rods and coring tubes in place.

Figure 4 is a perspective illustrating the manner in which my stirrup supports and spaces the reinforcing rods and coring tubes used in reinforcing and coring a cementitious structural member while it is being poured and set to harden.

I shall now point out the features of practical merit in my invention as I describe the same in comprehensive detail.

I am aware of the existence of numerous types and constructions of supports and spacers for inserts used in preparation of molded products; but the special function and novel construction of my stirrup will be readily noted as the economical,

simple and practical merits thereof are disclosed herein.

For instance, when preparations are being made to pour and set a cementitious structural member, 1, which will have in it some reinforcing rods and longitudinal cores then my stirrup is utilized to a marked advantage, as is shown in Figures 3 and 4.

In a study of the drawing, it will be noted that for the purposes of my invention, the form shown in Figure 1, and that shown in Figure 2, will have an equal merit in utility.

In regard to the practical servicable merits of my stirrup, for instance, it will be observed that in the making of a structural member 1 which is poured in forms 2, I will set a number of my stirrups 3 into their desired positions preferably in a uniformly spaced arrangement between spaced forms 2 and throughout their length, so that stirrups 3 may be permitted to effectively provide a substantial support for reinforcing rods 4, 5, 6, 7 and 8, when they are placed in the relative positions where they will be needed in the cementitious member 1 when it is poured.

In this way, a support for these reinforcing rods, while the cementitious member is being poured, is provided in a stirrup preferably formed of wire which will occupy a comparatively small space in the member.

In the manner in which these stirrups are transversely disposed in a number of places along the length of the structure, they will not only provide this support for the reinforcing rods but they will effectively add a reinforcing transverse stability to the structure member.

It will be noted that stirrups 3 are uprightly supported upon pins or legs 9 and 10 when they are set into place; while at the same time, it is true that if desired, these stirrups 3 could be provided with the supporting legs made by deforming the bottom cross-wire thereof in a manner that will provide supporting legs 11 and 12 in the form shown in Figure 4.

However, where legs 9 and 10 are provided as a pin construction as is shown in Figures 1, 2 and 3, then such supports will be secured in place preferably by welding.

It will be noted that the top wire 13 in my stirrup as is shown in the form illustrated in Figures 1, 3 and 4 is shaped to define terminal hooks 14 and 15 and a central supporting recess 16; while the bottom wire 17 of my stirrup is shaped to define terminal hooks 18 and 19 for the support of reinforcing rods 7 and 8 and to define lateral spacers, holding the stirrup against the forms 2.

A further purpose of my stirrup is to provide a substantial snug spacing support for coring tubes 20 and 21 which extend throughout the length of the forms 2 and are preferably made of paper tubing so that they may rot away after the structural form has been poured and set, or may be removed if desired. These paper tubes will hold up substantially for the time that they are needed to properly locate longitudinal spaced cores throughout the length of a cementitious structural member 1 when the cementitious material is poured into the forms over the reinforcing rods and coring tubes and permitted to set. The longitudinal cores are in this manner properly shaped in the structural member.

In Figure 1, I have illustrated the circular supports 22 and 23 for coring tubes 20 in the form in which they would be made as complete circles welded to wires 13 and 17; while in Figure 2, I have shown that a similar stirrup may be made by coiling the top wire 24 in a manner defining terminal hook 25, central supporting recess 26; circular loop 27 and terminal hook 28; and, at the same time, it would be a practical construction to shape the bottom wire 27 in a manner defining terminal hook 30, circular loop 31, and terminal hook 32 with pin or leg members 9 and 10 welded to the bottom wire 29.

Thus, it will be observed that in my invention, I am providing for a substantial means of supporting and spacing the reinforcing rods and coring tubes in one of the structural members for which my stirrup is made.

It is obvious that my stirrups could be made in not only one of several forms and materials but for the sake of explanation of the merits of my invention, I have illustrated the preferred forms thereof, realizing, for instance that my stirrups could be stamped, formed or molded and that instead of terminal hooks if it should be desired, loops or eyes could be provided, but these hooks will afford an opportunity for the reinforcing rods to be laid in place rather than threaded through such loops.

Having thus described the nature of my invention, what I claim is:

1. A supporting and spacing stirrup for spacing and supporting reinforcing rods and coring tubes while pouring and setting cementitious structural members, and comprising in integral combination a pair of integral wire members secured together; one of said wire members shaped to define terminal upturned hooks and a central dip on the same level with said hooks and into which reinforcing rods may be laid on the same level and also to define an integral circular downward loop therein providing a wire support for a coring tube; the other of said integral wire members shaped to define terminal upturned hooks for spacing and respectively supporting reinforcing rods at its terminals and to define an

upturned circular loop for the spaced support of a second coring tube; said loops establishing connection between said supporting wire members, and said stirrup provided with a pair of spaced integral wire supporting legs for holding the same in upright position off the bottom of a form used for molding said structural members.

2. A supporting and spacing stirrup comprising in integral combination, a plurality of spaced 10 wires shaped to define in each, spaced deformations for supporting reinforcing rods, a pair of spaced arcuate wire members establishing connection between said rod supporting wires for supporting coring tubes, and a plurality of integral wire supporting legs for said stirrup.

3. In a supporting and spacing stirrup, the combination of a plurality of wire members shaped to define spaced horizontally disposed rod support members provided with integral deformations defining holding means for horizontal 20 reinforcing rods, with integral spaced arcuate loop members establishing integral connection between said deformed wire rod supports for encompassing and supporting coring tubes, and a plurality of supporting legs for holding said stirrup.

4. A supporting and spacing stirrup for holding reinforcing rods and coring tubes and comprising, in integral combination, a plurality of spaced horizontally disposed wires formed at

30 their terminals to define upturned outwardly extending hook members providing rod supports and lateral stop members while in a molding form, said wire members also deformed intermediate their ends to define reinforcing rod spacers and supports, a pair of arcuate spaced integral wire members for encompassing and holding parallel spaced coring tubes and establishing integral connection between said spaced wire members, and a plurality of supporting legs for said stirrup.

5. A supporting and spacing stirrup for holding reinforcing rods and coring tubes while pouring and setting cementitious materials and comprising in integral combination, a plurality of parallel spaced wire members horizontally disposed, and each shaped to define terminal hooks and intermediate wire pockets for holding said rods, a pair of integral spaced arcuate wire members establishing integral connection between said parallel rod supporting wires for said coring tube support, one of said arcuate wire members deformed in shape to hold one side of one of said cores, and the other of said arcuate members deformed in shape to hold the opposed side of one of said cores, said stirrup provided with a pair of spaced integral supporting pins defining legs for the upright support of the stirrup.

EMMETT V. POSTON.
